UNITED STATES PATENT OFFICE

168,609

COMBINED VAPORIZER CASING AND MOUNTING BRACKET

Samuel Wichansky, Elizabeth, N. J., assignor to Remington Products Corporation, Elizabeth,
N. J., a corporation of New Jersey

Application March 22, 1950, Serial No. 8,705

Term of patent 7 years

(Cl. D31—3)

To all whom it may concern:

Be it known that I, Samuel Wichansky, a citizen of the United States, residing in the city of Elizabeth, Union County, State of New Jersey, have invented a new, original, and ornamental Design for a Combined Vaporizer Casing and Mounting Bracket, of which the following is a specification, reference being had to the accompanying drawings, forming a part hereof.

Fig. 1 is a perspective view of a combined vaporizer casing and mounting bracket showing
my new design;

Fig. 2 is a top plan view thereof; and

Fig. 3 is an end elevational view thereof.

The dominant features of my design reside in the portions shown in full lines.

I claim:

The ornamental design for a combined vaporizer casing and mounting bracket, substantially as shown and described.

SAMUEL WICHANSKY.
